Primary Examiner — Cathy Anne MacCormac*(74) Attorney, Agent, or Firm* — Price Heneveld LLP(57) **CLAIM**

I claim the ornamental design for a disposable litter liner, as shown.

DESCRIPTION

FIG. 1 is a top perspective view of a disposable litter liner;
FIG. 2 is a bottom perspective view thereof;
FIG. 3 is a first side view thereof;
FIG. 4 is a second side view thereof;
FIG. 5 is a third side view thereof;
FIG. 6 is a fourth side view thereof;
FIG. 7 is a top plan view thereof;
FIG. 8 is a bottom plan view thereof;
FIG. 9 is a top perspective view of the disposable litter liner in an alternate and flat configuration;
FIG. 10 is a top plan view of FIG. 9;
FIG. 11 is a bottom perspective view of FIG. 9; and,
FIG. 12 is a bottom plan view of FIG. 9.
